UNITED STATES PATENT OFFICE.

GEORGE A. JOHNSON, OF CHICAGO, ILLINOIS, ASSIGNOR TO WILLIAM H. MINER, OF CHICAGO, ILLINOIS.

DRAFT-YOKE AND DRAW-BAR CONNECTION IN RAILWAY DRAFT-RIGGING.

1,128,320.

Specification of Letters Patent. Patented Feb. 16, 1915.

Application filed September 13, 1912. Serial No. 720,152.

To all whom it may concern:

Be it known that I, GEORGE A. JOHNSON, a citizen of the United States, residing at Chicago, in the county of Cook and State of Illinois, have invented a certain new and useful Improvement in Draft-Yoke and Draw-Bar Connections in Railway Draft-Rigging, of which the following is a full, clear, concise, and exact description, referring once being had to the accompanying drawings, forming a part of this specification.

My invention relates to improvements in the means of connecting the draft yoke to the draw-bar in railway draft rigging.

15 The object of my invention is, to provide a simple and efficient means of connecting the draw-bar to the draft yoke in railway draft rigging.

In the drawings forming a part of this specification, Figure 1 is a plan view, partly in central horizontal section, of a means of connecting the draft yoke and draw-bar embodying my invention. Fig. 2 is a side elevation of the structure shown in Fig. 1. Fig. 3 is a vertical cross section taken on line 3—3 of Fig. 2. Fig. 4 is a vertical longitudinal section taken substantially on line 4—4 of Fig. 1. Fig. 5 is a view similar to Fig. 1, showing another form of my improvements, the sectional portion thereof being taken substantially on line 5—5 of Fig. 6. Fig. 6 is a side elevation of the structure shown in Fig. 5. Fig. 7 is a vertical section taken substantially on line 7—7 of Fig. 6. Fig. 8 is a longitudinal vertical section taken substantially on line 8—8 of Fig. 5.

Referring to the drawings, 9 represents the upper, and 10 the lower limb of a draft yoke of which the forward ends only are shown in the drawings. The draw-bar is represented by the reference 11, and 12 denotes a key, preferably flat, and vertically disposed in the vertical openings 13—13 in the forward portions of the upper and lower limbs of the yoke, and registering with the vertical perforation 25 in the draw-bar. The key 12, as shown, is made in two sections, the upper section 14, and lower section 15 being each provided with interengaging tongues 16—16, and, as will be apparent, the sections 14 and 15 are similar in form and shape. Through the tongues 16—16 the vertical key 12 is provided with a transverse perforation 17 registering with the perfora-

tions 18—18 in the sides of the draw-bar, and adapted to receive the transverse key 19. The key 19 is provided with a head 20 at one end, and with a perforation 21 at the other end to receive a cotter pin 22. By referring to the drawings, particularly Figs. 1, 2 and 3, it will be seen that the sides of the butt of the draw-bar are recessed or countersunk adjacent the portions in which the holes 18—18 are provided, so that the ends of the key 19 lie well within the planes of the sides of the coupler butt. A vertical key 12 is provided at either end with a head 24, which extends over the portions of the ends of the yoke arms surrounding the recesses 13—13 therein.

To remove the draw-bar, the cotter 22 is first withdrawn, after which the key 19 may be taken out, thus releasing the sections of the vertical key 12, which may be then withdrawn and the draw-bar removed. This operation is reversed when the draw-bar is assembled with the yoke.

In the form of my device shown in Figs. 5 to 8 inclusive, the draw-bar 26 is provided with a vertical opening 27 to receive the vertical key 28 which passes through slots 29 and 30 provided, respectively, in the upper limb 31 and the lower limb 32 of the draft yoke 33. The key 28, shown in these figures, is in one piece, and is provided at each end with a head 34, the ends of which extend over the portions of the yoke arms surrounding the slots 29 and 30 therein. Intermediate its ends, the key 28 is provided with a transversely extending perforation 35 to receive the pin or bolt 36, the latter passing through registering transverse slots 37—37 in the side walls of the draw-bar. The slots 37 are sufficiently elongated longitudinally of the draw-bar to permit the pin or bolt 36 to slide therein in relative movements of the draw-bar 26 and key 28. The bolt is provided at one end with a head 38, and the other end is threaded to receive a nut 39. In the form just described, it will also be noted that the side walls of the draw-bar are countersunk or recessed so that the head of the bolt and nut are adapted to lie within the planes of the sides of the draw-bar. The slots 29 and 30 in the limbs of the draft yoke, and the vertical slot 27 in the draw-bar are each longer than the width of the key 28 to permit limited longitudinal movement of the latter in ref.

erence both to the draw-bar and yoke, and are of sufficient length to permit the passage of the head 34 of the vertical key 28 when said slots are alined.

5. In normal position of the parts, and upon forward movement of the draw-bar, the front edge of the vertical key 28 engages with the front ends of the slots 29 and 30 in the limbs of the draft yoke, and the rear edge of the key with the rear edge of the vertical slot in the draw-bar.

Upon rearward movement of the draw-bar, the transverse slot 37 permits of relative movement between the draw-bar and vertical key 28, thus permitting the front edge of the vertical key 28 to engage the front edge of the vertical slot 27 in the draw-bar.

I claim:

1. In a railway draft rigging, a draft 20 yoke and a draw-bar; a key in sliding engagement with the draw-bar and slidingly engaging the yoke and removable means passing through said key to secure the same within the draw-bar said means being located entirely within the planes of the side walls of the draw-bar.

2. In a draft rigging, a draw bar, a draft yoke, a pin, and a key slidingly engaging the draw bar and the yoke, the pin passing 30 through the key and slidingly engaging the draw bar.

3. In a draft rigging, a slotted draw bar, a slotted yoke, a key slidably engaging the draw bar and the yoke within the slots there- 35 of, and means to secure the key within said slots, said means slidingly engaging the draw bar and the key.

4. In a draft rigging for railway cars, a draft yoke, a draw bar, a key and a pin, 40 the key having an enlarged head, the yoke and draw bar each having registering slots adapted for the passage of said head, the key being of lesser width than the slots to

permit a limited sliding movement of the key in all of said slots, the pin passing 45 through the draw bar and key to hold the key within said slots.

5. In a draft rigging for railway cars, a draft yoke, a draw bar, a key and a pin, the key having an enlarged head, the yoke and 50 draw bar each having registering slots adapted for the passage of said head, the key being of lesser width than the slots to permit a limited sliding movement of the key in all of said slots, the pin passing 55 through the draw bar and key to hold the key within said slots, said pin being in sliding engagement with the draw bar.

6. In a railway draft rigging, a draft yoke, a draw-bar, said draw-bar being 60 countersunk on the sides thereof, and provided with transversely extending recesses therethrough, a vertically arranged key connecting said draw-bar and draft yoke, and passing through vertically alined recesses 65 therein, and a removable member passing through said key and the transversely extending slots in the draw-bar, the ends of said member being located within said countersunk portions of the draw-bar. 70

7. In a railway draft rigging, a draft yoke, a draw-bar, said yoke and draw-bar being provided with vertically alined slots, a vertically extending key passing through said slots and adapted to connect the yoke 75 and draw-bar, said key having enlarged ends, portions of which extend over the metal of the yoke arms surrounding the slots therein, and a removable member extending transversely through the draw-bar and said 80 key for holding the latter in place.

GEORGE A. JOHNSON.
